ABSTRACT OF THE DISCLOSURE

Disclosed herein is a transportable live bait container which can be connected by a balanced type double valve coupling assembly to allow for the free flow of water into and out of the container when the container is placed in a boat. The coupling assembly is provided with normally closed valve members which are spring biased so that both valve members are opened on connection of the coupling assembly to allow for the free flow of water through the hose.

BACKGROUND OF THE INVENTION

This invention relates to live bait containers and to a doubled valved coupling assembly for connecting the container to the water outside of a boat. Live bait such as minnows or frogs are generally kept in a container such as a pail or bucket which is filled with water and placed in the bottom of a boat. The water in the pail must be changed periodically or it will become stagnant causing the bait in the container to die. A number of devices have been designed to prevent the water in such containers from becoming stagnant but these generally involve costly recirculating systems or redesigns of the boat hull in order to accommodate the system. These devices are also permanent type installations requiring a second container for transporting the live bait to and from the boat.

SUMMARY OF THE INVENTION

In the present invention a transportable type live bait container is placed in the bottom of a boat and connected directly to the water outside of the boat to allow the water to flow into and out of the container. The water level within the container will then always be at the same level as the water level outside of the boat. As the boat rocks the water level in the container will rise above or drop below the level of the water on the outside of the boat and water will either flow out of or into the container. The container can also be quickly drained by merely raising the container while it is connected to the outside of the boat to remove the bait and then replaced on the bottom of the boat to refill the container.

A valved coupling assembly is used to interconnect the container and an inlet attachment provided in the bottom or side of the boat or transom. The coupling assembly includes a first normally closed valve member provided at the end of the hose which is connected to the inlet attachment and a second normally closed valve member connected to an opening in the container. When the container is placed in the boat the valve members are connected and interlocked and the connecting motion used to open both valve members. Water will then be free to flow into and out of the container.

Other objects and advantages of the present invention will become more readily apparent from the following detailed description when read in connection with the accompanying drawings in which:

FIG. 1 is an end view in section of the boat showing the container in the bottom of the boat.

FIG. 2 is an exploded view in perspective of the coupling assembly.

2

FIG. 3 is a view in section showing a connected coupling assembly.

FIG. 4 is a view in section of a disconnected coupling assembly.

FIG. 5 is a view in section of the inlet attachment for the hose on the boat hull.

Referring specifically to the figures in the drawing, a transportable live bait container 10 shown in the form of a minnow pail is positioned on the bottom 12 of a boat 14. Water from the outside of the boat is allowed to flow freely into and out of the container through a hose 16 connected to an inlet attachment or connecting means 18 mounted in the transom 20 of the boat and a double valved coupling assembly 21 provided at the end of the hose and in the container. The water line 22 in the container and the water line 24 of the water on the outside of the boat will always tend to be on the same level. If the boat rocks counterclockwise about center line 25 of the boat, the water level in the pail will be below the water level outside the boat and water will tend to flow into the container. The same action occurs if the boat rocks fore and aft. Since a boat normally rocks periodically when in the water, there will be a fairly continuous circulation of water into and out of the container. In the event that the boat remains stationary, the container can be emptied and refilled by merely raising the container and allowing some of the water to drain.

The inlet attachment in the side wall of the boat includes a threaded tubular fitting 26 having a gasket or seal 32 located adjacent flange 30 on one end of the fitting. The fitting is inserted through a hole 28 located below the water line in the side wall 20 of the boat until flange 30 and gasket 32 abut the side wall. The flange is brought up tight against gasket 32 and the side wall of the boat by screwing nut 34 onto the fitting. The end 36 of the hose 16 is pushed onto the fitting and secured tightly thereto by band type clamp 38.

The other end 37 of the hose is closed by valved coupling member or means 40 (FIGS. 2, 3, and 4) which includes a cylindrical housing 42 having a tubular extension 44 that is inserted into the end of the hose and sealed by a clamp 70. A cylindrical valve cap 52 is biased by a compression spring 56 seated on flange 55 into engagement with valve seat 66 on flange 58 in retainer cap 46. The cap is retained in the bore 48 of the housing by pins 50 with an O-ring seal 64 positioned in the gap between flange 51 and the housing. Guides or spacers 54 are provided on the inner surface of the retainer cap to support the valve cap for axial motion in the retainer cap. A second O-ring seal 62 is mounted on the front of valve cap to engage valve seat 66 and seal the opening in the housing 42.

The housing 42 for coupling member 40 is formed for insertion into a valved wall coupling member or means 72 mounted in aperture 74 in the side wall of the container. The coupling member 72 includes a tubular housing 76 which is inserted into aperture until flange 78 abuts the side wall of the container. A gasket 80 is positioned between the flange 76 and side wall to seal the housing in the aperture. Any means such as screw 82 and self-sealing nut 84 can be used to hold the housing 76 on the container.

The passage 86 in the housing 76 is normally closed by valve disc 88 which is biased by compression spring 100 into engagement with a valve seat 90 on flange 92. A snap ring 102 is pushed into a groove 104 in passage 86 to retain the spring in housing 76. The valve disc has a number of spacer or guide knobs 94 around its outer periphery to guide the disc for axial motion in passage 86 and an O-ring seal 98 to sealingly engage the valve seat.

The normally closed valve members are opened when the hose coupling member is inserted into and interlockingly engaged with the wall coupling member. A valve opening means such as valve stem 106 on valve disc 88 is axially aligned with valve cap 52 and engages the center of the valve cap when the hose coupling member 42 is inserted into the wall coupling member 76. The valve stem is made longer than the distance between the valve seats 66 and 90 and when the valve coupling members are connected the valve stem will hold the valve cap and valve disc apart a distance greater than the distance between the valve seats (FIG. 3). The spring force of both spring 56 and spring 100 is approximately equal and as a consequence both the valve cap and valve disc will be unseated from their respective valve seats. It should be noted that the valve stem could be mounted on the valve cap or could take a different form and accomplish the same result.

To connect and lock the hose coupling member 40 to the wall coupling member 72, pin 108 on housing 42 is aligned with L-shaped slot 110 on housing 76 and housing 42 pushed into housing 76 until cap 46 abuts flange 92. O-ring seal 64 seals the joint between housing 42 and retainer cap 46, and also seals both the housing 42 and cap 46 in housing 76. Housing 42 is then rotated to seal pin 108 in recess 112 at the end of slot 110. The valve stem will engage the valve cap as the housing 42 is inserted into housing 76 and will force valve cap 52 and valve disc 88 away from their respective valve seats.

Both valves will then be opened and water will be free to flow through the hose into or out of the pail. On disconnection, the housing 42 is twisted until pin 108 is properly aligned in slot 110 and housing 42 pulled out of housing 76. The compression springs will move the valve disc and valve cap back into engagement with their respective valve seats closing the passages in both housings.

In the device as disclosed, the coupling assembly has been shown and described as mounted on the live bait container. It should be apparent, however, that the coupling assembly could also be mounted on the side wall of the boat and the base attached to the live bait container.

Although only one embodiment of the present invention has been shown and described it should be apparent that various changes and modifications can be made herein without departing from the scope of the invention.

What is claimed is:

1. The combination with a boat and a transportable live bait container of means adapted to allow for the free flow of water from the outside of said boat into said container, said means comprising,
  - a hose,
  - connecting means in the side wall of said boat for connecting said hose to the water outside of said boat, first valved coupling means in said hose,
  - a second valved coupling means in said container, said first and second coupling means being adapted for interlocking engagement,
  - and valve opening means to open both valved coupling means on engagement of said first and second coupling means.
2. The combination according to claim 1 wherein said first valved coupling means comprises
  - a first housing connected to said hose, and having a valve seat and a valve cap biased toward engagement with said seat,
  - and said second valved coupling means comprises a second housing having a valve seat and a valve disc biased toward engagement with said valve seat.
3. The combination according to claim 2 wherein said valve opening means comprises a stem positioned between said valve disc and valve cap.
4. In a boat having an inlet attachment, a live bait container connected to said inlet attachment in said boat to allow for the free circulation of water from out-

side the boat into the container, said container including a wall coupling member located in the side wall of said container, said member having a passage and a valve seat within said passage, a valve disc mounted for movement into engagement with said valve seat,

a spring normally biasing said valve disc into engagement with said valve seat, and valve opening means connected to the inlet attachment to open said valve only on connection of the inlet attachment to said wall coupling member.

5. A device according to claim 4

wherein said valve opening means includes a hose connected to the inlet attachment and a normally closed valve coupling member connected to said hose, said normally closed valve coupling member being opened by said valve opening means only on connection to said wall coupling member.

6. In a boat having an inlet attachment, a live bait container connected to said inlet attachment in said boat to allow for the free circulation of water from outside the boat into the container, of means for connecting said container to said boat comprising

a first normally closed valve coupling member connected to said container, a second normally closed valve coupling member connected to said inlet attachment, said second coupling member including a tubular housing, a retainer cap positioned in said housing and having an internal flange forming a valve seat, pin means securing said cap to said housing, a valve means in said housing biased into engagement with said valve seat

and valve opening means to move said valve means off of said valve seat when said first coupling member is mounted on said second coupling member.

7. A device according to claim 6

wherein said first valve coupling member comprises a tubular housing having an internal valve seat, a second valve means biased into engagement with said internal valve seat,

whereby said valve opening means opens both valve means on connection of said coupling members.

8. The combination of a boat, a transportable live bait container adapted to be positioned in the bottom of the boat and disconnectable coupling means to allow for the free flow of water into and out of the container, said coupling means comprising

a flexible conduit connected to the boat, a pair of complementary coupling members joined to said conduit and said container, each of said coupling members including a housing having a valve seat and a valve member biased toward engagement with said seat, a valve stem positioned to open said valve members only when said coupling members are connected, said seat on one said housing comprising an annulus, and an O-ring sealing said annulus constantly to one said housing, and temporarily to the other said housing when said parts are connected.

9. The device of claim 8 wherein at least one said valve member is sealed with an O-ring, and radial guide members on said valve member to guide said valve members within said housing.
